(57) **CLAIM**

The ornamental design for a wireless earphone case, as shown and described.

DESCRIPTION

FIG. 1 is a front perspective view of a wireless earphone case of the present invention.

FIG. 2 is a back perspective view of FIG. 1.

FIG. 3 is a front view of FIG. 1.

FIG. 4 is a back view of FIG. 1.

FIG. 5 is a left side view of FIG. 1.

FIG. 6 is a right side view of FIG. 1.

FIG. 7 is a top plan view of FIG. 1.

FIG. 8 is a bottom plan view of FIG. 1; and,

FIG. 9 is a perspective view showing a state of use of the wireless earphone case of FIG. 1 which holds the wireless earphones. The broken lines in the figure are for the purpose of illustrating environmental structure and form no part of the claimed design.
